UNITED STATES PATENT OFFICE.

ARILD M. BRENN, OF CHICAGO, ILLINOIS, ASSIGNOR, BY MESNE ASSIGNMENTS, TO
W. H. MINER, INC., A CORPORATION OF DELAWARE.

FRICITION SHOCK-ABSORBING MECHANISM.

Application filed December 26, 1922. Serial No. 608,825.

To all whom it may concern:

Be it known that I, ARILD M. BRENN, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock absorbing mechanisms.

One object of the invention is to provide a friction shock absorbing mechanism especially adapted for railway draft riggings, wherein are obtained high capacity and easy release.

Another object of the invention is to provide, in a mechanism of the character indicated, means automatically operable, in compensating for wear, to gradually increase the effective wedging angle so that loss in capacity otherwise resulting from setting of the springs and loss in initial compression of the springs, is thus offset or counterbalanced.

A still further object of the invention is to provide, in a mechanism of the character indicated, a wedging system of relatively keen angle character at the initiation of a compression stroke, which wedging system gradually changes, during the progress of the compression stroke, to a wedge system having a blunter effective wedging angle so that, in obtaining the desired total capacity, a higher initial frictional resistance may be employed in the compression stroke with a resulting lesser ultimate peak load, thereby reducing the ultimate shocks transmitted to the car underframe.

Other objects of the invention will more clearly appear from the description and claims hereinafter following.

In the drawings forming a part of this specification, Figure 1 is a horizontal longitudinal sectional view of a portion of a railway draft rigging showing my improvements in connection therewith. Figure 2 is a front end elevational view of the shock absorbing mechanism proper. Figure 3 is a broken vertical longitudinal sectional view corresponding to the section line 3-3 of

Figure 2. And Figures 4 and 5 are detail perspectives of one of the wedge elements 55 and a spring cap, respectively.

In said drawings, 10-10 denote channel draft sills of a car underframe to the inner faces of which are secured front stop lugs 11 and rear stop lugs 12. A portion of a draw bar is indicated at 13, the same being operatively associated with the shock absorbing mechanism proper by a hooded cast yoke 14 within which is disposed the shock absorbing mechanism proper and a front follower 15. The yoke and parts therewithin are supported in operative position by a detachable saddle plate 16.

The improved shock absorbing mechanism proper, as shown, comprises a combined 70 friction shell and spring cage casting A; four main spring resistances B-B; a fifth spring resistance C; a pair of friction shoes D-D; a pair of wedge elements E-E; a spring cap F; a pair of compensating wedge 75 elements G-G; and a combined retainer and fulcrum pin H.

The casting A, as shown, is of rectangular cross section having top and bottom walls 17-17, integral rear vertical wall 18 acting as the rear follower of the mechanism, and two side walls 19-19, the latter being made relatively short so as to leave the major portion of the sides of the casting A open to permit of the insertion and removal 85 of certain of the parts. The inner faces of the side walls 19 are preferably recessed as indicated at 20 to accommodate special wear resisting blocks or liners 21-21, each of the latter being provided on its inner side 90 with a longitudinally extending flat friction surface 22, said surfaces converging inwardly of the shell.

The two shoes D are of like construction, each being in the form of an elongated 95 member having an outer flat friction surface 23 cooperable with a shell friction surface 22. On its inner side, each shoe D is provided with a concave bearing surface 24, the latter corresponding to the section of a 100 cylindrical surface, the center of which is located in a radius perpendicular to the wedge face of one of the wedge elements E hereinafter described. At their inner ends, the shoes D bear upon a spring follower 25, 105 which in turn bears upon the four main

spring resistances B, the latter being uniformly arranged in the four corners of the spring cage portion of the casting A.

The two wedge elements E are of like construction, each having a front bearing face 26 engaging the inner side of the front main follower 15. Each wedge element E is further provided, near its inner end, with a wedge face 27, the latter converging inwardly of the shell and extending at a comparatively acute or keen angle with respect to the axis of the mechanism and the line of applied compression forces. Each wedge element E is further provided, on its inner side, with a curved bearing surface 28 within which is seated a pin H, the latter providing a fulcrum for the two wedge elements E and thus adapting the latter to rock or tilt with respect to each other and with respect to other parts of the mechanism. Stated in another manner, the wedge of the friction unit may be said to consist of two rocker elements having their wedge faces relatively adjustable, for the purposes hereinafter described.

Interposed between each wedge element E and the corresponding shoe D is one of the elements G, the latter being segmental in cross section and having each an outer convex surface 29 cooperating with the corresponding concave surface 24. On the side adjacent the axis of the mechanism, each element G is provided with a flat face 30 cooperable with the corresponding wedge face 27.

The centrally disposed spring C is made longer than the other springs B and is extended through a central aperture 31 in the follower 25. To the forward end of the spring C is applied the spring cap F which has a forwardly projecting section 32 of wedge-shape, thus providing two wedge faces 33—33. The latter cooperate with curved bearing faces 34 so arranged that relative adjustment between the element F and the wedge elements E is permitted.

The operation of the mechanism, assuming a compression stroke in buff, is as follows. As the pressure is applied to the follower 15 and from the latter transmitted to the wedge elements E, the bearing elements G and shoes D will be forced inwardly of the shell. The initial effective wedging angle will correspond to the included angle between the two wedge faces 27. As the elements are forced inwardly of the shell, the shoes D will approach each other laterally, due to the tapered friction shell surfaces 22. This relative lateral approach of the two shoes D is compensated for by rocking of the two elements E upon the fulcrum pin H in such manner that the inner ends of the elements E will laterally approach each other, thereby squeezing out the wedge shaped spring cap F. It will be obvious

that this action is accommodated by reason of the cooperating concave and convex bearing surfaces on the shoes D and bearing members G, respectively. As this action occurs, it is apparent that the included angle between the wedge faces 27 will gradually increase, thus producing a wedging system of blunter angle effect than was present at the initiation of the compression stroke. With this construction, in obtaining a predetermined total capacity for the mechanism, I am enabled to use a comparatively keen angle to obtain high capacity at the initiation of the stroke with a consequently decreased ultimate or peak load at the end of the stroke. In carrying out my invention, the included angle between the faces 33—33 of the spring cap will be so chosen that a high lateral pressure will be maintained between the inner ends of the wedge elements E, but yet of sufficient bluntness as to permit the spring cap being squeezed out at a predetermined lateral pressure within the elastic limit of the shell. Stated in another manner, if the included angle between the wedge faces 33 of the spring cap F were made of such acuteness that the cap could not be squeezed out as the compression stroke takes place to permit collapse of the rocker wedge, the shell might be expanded beyond its elastic limit. In actual practice, the included angle between the wedge faces 33—33 will approximate about 40°.

Another important feature of the invention resulting from the construction shown and described, resides in the following. As wear occurs on the shell and shoe friction surfaces, the shoes D will separate laterally gradually as the mechanism remains in service. This allows the inner end of the rocker wedge to expand slightly, the action being induced by pressure derived from the spring cap F, it being understood that the spring C is placed in the gear under initial compression. This action on the rocker wedge obviously tends to decrease the included angle between the wedge faces 27—27, thereby increasing the effective wedging action of the wedge system. This has the effect of compensating for loss in capacity which might otherwise arise by reason of the springs taking some set, and also because of the reduced initial capacity in the spring C as the latter gradually lengthens, due to the forward movement of the spring cap F in taking up wear.

During the compression stroke, the friction shell will be expanded so that, upon removal of the actuating force, the energy stored up in the shell will re-act with forces directed inwardly toward the axis of the mechanism. These forces will be transmitted to the wedge E—E causing a slight further collapse thereof at the initiation of the release action, thus increasing the blunt-

ness of the included angle between the wedge faces 27-27 and facilitating the collapse of the friction unit.

The pin H, in addition to performing its function as a fulcrum for the wedge rocker elements E, also serves to retain the parts in assembled position. By referring to Figure 3, it will be noted that the pin H has its ends working in longitudinal recesses 50 provided on the inner side of the top and bottom walls of the castings A, said pin H being limited in its forward movement with respect to the casting. Due to the nature of the engagement between the pin H, and the rocker elements E, the latter will also be limited in their outward movement with respect to the casting A, and the same will be true of the remaining movable elements. The pin H may be introduced in the casting through a suitable opening 51 in the top wall thereof.

I have herein shown and described what I now consider the preferred manner of carrying out my invention, but the same is merely illustrative and I contemplate all changes and modifications that come within the scope of the claims appended hereto.

I claim:

1. In a friction shock absorbing mechanism, the combination with a friction shell; of a spring resistance; friction shoes cooperable with said shell; a collapsible pressure transmitting wedge including rocker parts; and angularly adjustable bearing elements between said parts of said wedge and said shoes.

2. In a friction shock absorbing mechanism, the combination with a friction shell having interior friction surfaces converged inwardly of the shell; of a spring resistance; friction shoes cooperable with said shell; a collapsible pressure-transmitting wedge including relatively rocking spreading members; and fulcrum-acting adjustable bearing elements between said rocking members of said wedge and the shoes.

3. In a friction shock absorbing mechanism; the combination with a friction shell; of a spring resistance; friction shoes cooperable with said shell; a wedge system cooperable with said shoes, said wedge system having an original predetermined effective wedging angle; and means interposed between said shoe and wedge system whereby the parts of said wedge system are adapted to automatically adjust themselves relatively to each other and relatively to the shoes as wear occurs on the friction surfaces of the shoes and shell, allowing the shoes to separate laterally, to thereby produce a gradually decreasing effective wedging angle.

4. In a friction shock absorbing mechanism, the combination with a friction shell having interior friction surfaces converged

inwardly of the shell; of a spring resistance; friction shoes cooperable with said shell; a wedging system cooperable with the shoes, said wedge system having an initial predetermined effective wedge angle at the 70 beginning of a compression stroke; and adjustable elements coacting with said shoes and wedge system whereby the parts of said wedge system are adapted to automatically adjust themselves relatively to each other 75 and relatively to the shoes, during a compression stroke, to increase the effective wedging angle.

5. In a friction shock absorbing mechanism, the combination with a friction shell 80 having interior friction surfaces converged inwardly of the shell; of a spring resistance; friction shoes cooperable with the shell, said shoes having adjustable means thereon presenting wedge faces; and a 85 wedging system consisting of a plurality of parts cooperable with said shoes, said wedging system having an original effective predetermined wedging angle automatically increasing by relative movement of the parts 90 of the wedge system as wear occurs on the shell and shoes, the parts of said wedge system also automatically adjusting themselves 95 relatively to each other and the shoes during a compression stroke in a manner to increase the wedge angle.

6. In a friction shock absorbing mechanism, the combination with a friction shell; of a spring resistance; friction shoes cooperable with said shell; a wedge system cooperable with said shoes, said wedge system having an original predetermined effective 100 wedging angle; and angularly adjustable means between said wedge system and shoes whereby the parts of said wedge system are adapted to automatically adjust themselves relatively to each other and relatively to the shoes as wear occurs on the friction surfaces of the shoes and shell, allowing the 105 shoes to separate laterally, to thereby produce a gradually increasing effective wedging angle, said wedge system including two elements pivotally mounted with respect to each other.

7. In a friction shock absorbing mechanism, the combination with a friction shell having interior friction surfaces converged inwardly of the shell; of a spring resistance; friction shoes cooperable with said shell, said shoes having angularly adjustable means thereon; and a wedging system cooperable with angularly adjustable means on the shoes, said wedge system having an initial predetermined effective wedge angle at the beginning of a compression stroke, the parts of said wedge system automatically adjusting themselves relatively to each other and relatively to the shoes, during a compression stroke, to increase the effective 115 wedging angle, said wedge system including 120

125

130

two elements pivotally mounted with respect to each other.

8. In a friction shock absorbing mechanism, the combination with a friction shell having interior friction surfaces converged inwardly of the shell; of a spring resistance; friction shoes cooperable with the shell; a wedging system consisting of a plurality of parts cooperable with said shoes, said wedge system having an original effective predetermined wedging angle; means coacting with said wedge system for automatically decreasing the wedging angle by relative movement of the parts of the wedge system as wear occurs on the shell and shoes; and angularly adjustable means between said wedge system and shoes whereby the parts of said wedge system also automatically adjust themselves relatively to each other and the shoes during a compression stroke in a manner to increase the effective wedging angle, said wedge system including two wedge elements pivotally mounted with respect to each other.

9. In a friction shock absorbing mechanism, the combination with a friction shell having interior friction surfaces converged inwardly of the shell; friction shoes cooperable with the shell; a pair of relatively fulcrumed pressure transmitting wedge elements; a follower coacting with said elements; means for yieldingly resisting movement of said follower and shoes; and bearing elements interposed between said wedge elements and the shoes, said bearing elements and the shoes having cooperating curved bearing faces and said bearing elements and the wedge elements having flat engaging faces.

10. In a friction shock absorbing mechanism, the combination with a friction shell having interior friction surfaces converged inwardly of the shell; of a spring resistance; friction shoes cooperable with the shell; a pair of rocker pressure transmitting elements; spreading means coacting with said elements; an auxiliary spring resistance coacting with said means; and bearing members interposed between said elements and the shoes, said bearing members having curved bearing surfaces on one side and flat wedge-acting faces on the other side.

11. In a friction shock absorbing mechanism, the combination with a friction shell; of a main spring resistance; friction shoes

cooperable with the shell; relatively pivotally mounted wedge elements; adjustable bearing members between said wedge elements and the shoes; a wedge-shaped cap, 60 disposed between and cooperating with the inner ends of said wedge elements; and spring means opposing movement of said cap inwardly of the mechanism.

12. In a friction shock absorbing mechanism, the combination with a friction shell; of a spring resistance; friction shoes cooperable with the shell, a pair of pressure-transmitting wedge elements fulcrumed intermediate their ends; adjustable bearing 70 members between said elements and the shoes; and a spring supported wedge-shaped cap disposed between and cooperating with the inner ends of said wedge elements; and an additional spring resistance coacting with 75 said cap.

13. In a friction shock absorbing mechanism, the combination with a friction shell having interior friction surfaces converged inwardly of the shell; of friction shoes cooperable with the shell; a spring resistance for yieldingly resisting relative movement 80 between the shoes and shell; a pair of pressure-transmitting wedge elements fulcrumed intermediate their ends; adjustable bearing 85 members between said wedge elements and the shoes; a wedge-shaped spring cap cooperable with the inner ends of said wedge elements; and an independent spring for 90 said cap.

14. In a friction shock absorbing mechanism, the combination with a friction shell having interior friction surfaces converged inwardly of the shell; of opposed friction shoes cooperable with the shell, each shoe 95 having a concave bearing face on its inner side; a spring resistance for said shoes; a pair of pressure-transmitting wedge elements fulcrumed intermediate their ends; bearing members interposed between said 100 elements and the shoes and having curved bearing faces cooperable with the curved bearing faces of the shoes; a wedge-shaped spring cap fitting between and cooperating with the inner ends of said wedge elements; and an independent spring resistance for 105 said cap.

In witness that I claim the foregoing I have hereunto subscribed my name this 8th day of December, 1922.

ARILD M. BRENN.
